J. A. HEWES

MAN'S NECKWEAR

Filed March 22, 1923

FIG. 1.

FIG. 2.

Inventor:

James A. Hewes
by Chas. F. Perkins, Attorney

UNITED STATES PATENT OFFICE.

JAMES A. HEWES, OF MELROSE, MASSACHUSETTS, ASSIGNOR TO JAMES A. HEWES AND FRANK W. POTTER, COPARTNERS, DOING BUSINESS AS HEWES & POTTER, OF BOSTON, MASSACHUSETTS.

MAN'S NECKWEAR.

Application filed March 22, 1923. Serial No. 636,739.

To all whom it may concern:

Be it known that I, JAMES A. HEWES, a citizen of the United States, residing at Melrose, in the county of Middlesex and State of Massachusetts, have invented new and useful Improvements in Men's Neckwear, of which the following is a specification.

My invention relates to men's neckwear, and consists of an improvement in bow neckties having for its object the production of a bow resembling a bow tied by the wearer, in which means are provided for supporting the wings of the bow at the particular points requiring support, and in which the skeleton frame is a more simple structure than that heretofore devised for the purpose.

Fig. 1 is a front elevation of the tie showing in dotted lines the skeleton frame internally supporting the fabric.

Fig. 2 is an elevation of the supporting frame.

3, 3, are the wings of the tie. 4 is the knot. 5 is a strip of sheet copper or other suitable pliable metal, and 6, 6, are cross pieces of some stiff or non-pliable material such as paper or wood fibre, secured to the opposite ends of the strip 5 midway of their length.

30 In the Letters Patent issued to me June 13th, 1922, and numbered 1,419,137 I have described a bow tie containing a pliable metal frame for supporting and imparting a variety of shapes to the fabric of the tie.

35 I have found that in the ordinary use and wear of such bow ties the tendency is for the metal wire frame if made of fine guage wire to become compressed so that in time the wings of the tie partially lose their support and gradually become crushed and out of shape. In my application for Letters Patent of the United States, Serial Number 557,719, and filed May 1st, 1922, I have shown and described certain means for supporting the wings of a bow tie which also contain a pliable metal frame for imparting a variety of shapes to the tie; my present invention consists of a specific form of skeleton frame resembling the letter H for 40 accomplishing the above named objects,

which invention I have evolved from practical experience in making, selling and using bow ties of the character specified, and which I have found to possess ideal qualities for simplicity of structure, economy of manufacture and efficiency in use. I have discovered that by employing a narrow support of stiff material near the outer edge of the end of each wing and of nearly the same length as the width of the wing, such as the cross piece 6, and rigidly securing such supports at right angles to a pliable metal strip, such as 5, I can provide a frame for bow neckties which will enable the wearer to impart to the tie a shape and style to suit his individual taste, and to support the fabric of the wings at the points where it is needed and only at those points. I have found that if the corners 7, 7, of the wings are supported, the tie will keep its shape, and if not, the wings will be to some extent crumpled out of shape by the pressure of the neck and chin of the wearer. The cross pieces 6, 6, of the frame are adapted to keep the corners 7, 7, spread apart, and the cross pieces 6, 6, as well as the member 5, being narrow strips, occupy less space within the tie than the frame shown in my said Letters Patent and in my pending application, and therefore permit great freedom of movement in molding the tie to a shape to suit the wearer's taste.

I do not limit my invention to the dimensions or precise shape shown of the strip 5 nor to the particular material of which it is composed. While I prefer a flat strip of sheet copper about one-quarter of an inch wide, it may be made wider or narrower, or consist even of wire, and it may be made of any pliable metal and accomplish to a measurable extent the objects of my invention, and such structure would be within its scope. Neither do I limit my invention to the particular material of which the supports 6, 6 are composed, providing it possesses the characteristic of stiffness or non-pliability similar to that of paper or wood fibre. I prefer fibrous material to metal because of the tendency of the latter to chafe or cut the fabric.

What I claim and desire to secure by Letters Patent is:

A bow tie including a frame comprising a longitudinal member of pliable metal readily bendable to impart a variety of shapes to the tie, and narrow strips of rigid material secured to the ends of said longitudinal member and at right angles thereto, the length of each of said strips being ap-

proximately the width of the bow and located near its outer end.

In testimony whereof I have hereunto set my hand in presence of two subscribing witnesses, this first day of March, 1923.

JAMES A. HEWES.

Witnesses:

JOHN L. BRUMMETT,
PAUL F. PERKINS.
